UNITED STATES PATENT OFFICE.

JOHN REECE, OF ST. LOUIS, MISSOURI, ASSIGNOR TO EVR KLEAN SEAT PAD CO., OF ST. LOUIS, MISSOURI, A CORPORATION OF MISSOURI.

SEAT PAD.

Application filed January 11, 1922. Serial No. 528,528.

To all whom it may concern:

Be it known that I, JOHN REECE, a citizen of the United States, residing at St. Louis, Missouri, have invented a new and useful Seat Pad, of which the following is a specification.

This invention relates to seat pads.

An object of the invention is to provide an improved removable and interchangeable portable seat pad comprising a seat member and a back member pivotally united along adjacent edges and arranged so that they may be folded flat one against the other in either direction, and each member including a body portion of sufficient flexibility to permit bending to obtain proper adjustment to the curvature of the seat to which the pad may be applied, and of sufficient stiffness so that either member will remain extended vertically.

Another object of the invention is to provide an improved seat pad including seat and back members characterized as stated; in combination with a hinge device uniting the two members and comprising separate strips of flexible material secured to the adjacent edges of said members and secured together along the line between the adjacent edges of the two members to space said members so that they may be folded one upon the other with equal facility in either direction.

Other objects will appear from the following description, reference being made to the drawing, in which,

Fig. 1 is a view showing one of the sides of the seat pad with the two members thereof extended.

Fig. 2 is a similar view showing the opposite side of the seat pad.

Fig. 3 is a sectional view on the line 3—3 of Fig. 1.

In the embodiment of the invention shown my improved seat pad comprises a member 1 and a separate member 2. The members 1 and 2 may be and preferably are of porous material and are characterized by sufficient flexibility to bend readily to the contour and shape of the seat or support upon which they may be used, and one or both being characterized by sufficient stiffness so that it will remain in raised position without folding or crumpling upon itself. Straw matting is an appropriate material as it possesses the desired porosity and is characterized by suffi-

cient flexibility and by sufficient stiffness to obtain the desired results.

In the pad shown in the drawing the members 1 and 2 are of straw matting, said members being of sufficient size so that one 60 may be used as a seat member and the other as a back member.

A marginal reinforcement 3 of cloth or other suitable material is secured around each of the members 1 and 2. Along the 65 adjacent and side edges of each of the members 1 and 2 a relatively wide strip 4 of flexible and substantially non-elastic material is secured by lines of stitching 5 but the strips 4 are not necessary at the outer 70 edges of the seat and back members and are therefore omitted from the outer edges. As stated, the strips 4 are relatively wide so that the lines of stitching 5 near the inner edges of the strips 4 are relatively consider- 75 able distances from the edges of the members 1 and 2. The marginal reinforcements 3 are folded to enclose the marginal edges or borders of the members 1 and 2 and to enclose the outer edges of the strips 4. Lines of 80 stitching 6 passing through the folded edges of the reinforcements 3 and through the interposed portions of the wide non-elastic strips 4 securely hold the reinforcements 3 on the edges of said members. The strips 4 85 afford proper anchorage for the lines of stitching 6 preventing the reinforcements 3 from tearing off.

The hinge or pivotal connection for the members 1 and 2 is designed and intended 90 to permit said members to be folded flat one upon the other in either direction, and comprises a construction and arrangement by which the adjacent marginal edges of the members 1 and 2 are spaced sufficiently to 95 permit such folding. The hinge shown comprises two separate flexible strips 7 united by a row of stitching 8 formed longitudinally of said strips from end to end, and midway between the side edges thereof. The adjacent edges of the members 1 and 2 having the reinforcements 3 and the holding strips 4 thereon are placed between the members 7 at opposite sides of the row of stitching 8. Rows of stitching 9 are then applied adjacent to the edges of the strips 7 beyond the border reinforcements 3 and through the retaining strips 4 and the members 1 and 2. As shown, there are additional rows of stitching 10 between the rows of stitching 6 and 110

the marginal edges of the two members 1 and 2.

The row of stitching 8 holds portions of the strips 7 between the adjacent edges of the pad members and forms a spacer permitting the pad members to be folded flat one upon the other in either direction. This construction and arrangement, distinguishing my invention from others, permits the pad to be 5 reversed to use either side thereof as the seating surface and permits the back member to be folded flat upon the seat member irrespective of the side used as the seating surface of the pad. This highly desirable 10 feature practically doubles the life or period of usefulness of the pad, since in the case of pads in which only one side is adapted for use as the seating surface, such side frequently becomes damaged or soiled to such 15 an extent as to destroy or to detract from its usefulness. But, in case either side of the pad embodying the present invention becomes damaged or soiled so that it cannot well be used as the seating surface, the pad 20 may be reversed so as to bring into use the 25 other and undamaged side of the pad.

From the foregoing it is plain that my invention adequately obtains all of its intended objects and advantages. It is not so restricted that any specific material must be 30 used to form the seating and back members. It is important only that the seating and back members shall be characterized as 35 mentioned so as to adapt the pad for use upon seats of nearly every construction and form.

I do not restrict myself unessentially, but what I claim and desire to secure by Letters Patent is:—

40 1. As an article of manufacture, a seat pad comprising a seating member and a back member, each of which is characterized by sufficient stiffness to remain extended vertically and by sufficient flexibility to permit bending to the curvature of the seat and back of the support to which it may be applied, a border of flexible material enclosing the adjacent edge of each of said members, a pair of hinge strips covering said 45 borders and having their edges stitched to said members respectively beyond said borders, and said strips also being stitched to said members and to said borders near the 50

marginal edges of said members, and a row of stitching uniting said hinge strips and holding said strips together between the adjacent edges of said members and separating said borders from each other. 55

2. As an article of manufacture, a seat pad comprising a seating member and a back member, each of which is characterized by sufficient stiffness to remain extended vertically and by sufficient flexibility to permit bending to the curvature of the seat and back of the support to which it may be applied, a border of flexible material enclosing the adjacent edge of each of said members, a pair of hinge strips covering said borders and having their edges stitched to said members respectively beyond said borders, said strips also being stitched to said members and to said borders near the marginal edges of said members, a row of stitching uniting said hinge strips and holding said strips together between the adjacent edges of said members and separating said borders from each other, and relatively wide strips of flexible material secured to the side and adjacent edges of said members respectively. 65 70 75

3. As an article of manufacture, a seat pad comprising a seating member and a back member, each of which is characterized by sufficient stiffness to remain extended vertically and by sufficient flexibility to permit bending to the curvature of the seat and back of the support to which it may be applied, a border of flexible material enclosing the adjacent edge of each of said members, a pair of hinge strips covering said borders and having their edges stitched to said members respectively beyond said borders, and said strips also being stitched to said members and to said borders near the marginal edges of said members, a row of stitching uniting said hinge strips and holding said strips together between the adjacent edges of said members and separating said borders from each other, relatively wide strips of flexible material secured to the side and adjacent edges of said members respectively, 90 95 100 and relatively narrow continuations of said borders enclosing the outer edges of said wide strips along the side and adjacent edges of said members respectively.

JOHN REECE,
